UNITED STATES PATENT OFFICE.

BENJAMIN VIGDAL, OF ARMSTRONG, IOWA.

LOCKING CAN-COVER.

977,491.

Specification of Letters Patent.

Patented Dec. 6, 1910.

Application filed September 28, 1910. Serial No. 583,239.

To all whom it may concern:

Be it known that I, BENJAMIN VIGDAL, a citizen of the United States, residing at Armstrong, in the county of Emmet and 5 State of Iowa, have invented a new and useful Locking Can-Cover, of which the following is a specification.

It is the object of the present invention to provide an improved locking device for the 10 covers of milk cans and similar containers and one of the primary objects of the present invention is to so construct the locking means that it will not be in the way and will permit of the handle of the cover being 15 grasped as readily as the ordinary handle.

Another object is to provide a locking means for a can or similar cover which means is mounted upon the handle for the 20 cover and has formed through overlying parts, openings which register with each other and with an opening formed through the cover handle, it being intended that the hasp of a pad lock or the wire of a seal shall be secured through these openings so in the 25 first instance, to prevent removal of the cover without unlocking the lock, and, in the second instance, to prevent removal of the cover without destruction of the seal.

With the above and other objects in view, 30 the invention resides in the general construction and arrangement of parts shown in the accompanying drawings, in which,

Figure 1 is a top plan view of a container cover provided with the locking device embodying the present invention, the locking device being shown in full lines in position to lock the cover to the container and in dotted lines in position to permit of removal of the cover from the container. Fig. 2 is 40 a vertical transverse sectional view through the cover and the locking device.

In the drawings, there is shown a cover such as is used on the ordinary milk can and this cover is indicated in general by 45 the reference numeral 5, it being provided upon its upper side with the usual handle 6 of ordinary form except that it includes an extension 7 upon which the locking device embodying the present invention is to 50 be mounted, as will be presently explained.

At diametrically opposite points, the wall of the body of the cover 5 is formed with openings indicated by the numeral 8, these openings being located beyond the ends of 55 the handle 6 upon the cover for a purpose which will be presently explained. Secured

upon the said wall of the cover body at each opening is a guide 9. A locking bolt 10 and a locking bolt 11 are slidably fitted at their outer ends through the guides 9 and in position to project through the corresponding openings 8. Inwardly of their said ends, the bolts are preferably flat and at their inner ends they are pivoted as at 12 and 13 respectively, to the under side of an operating handle 14. This handle is pivoted, as at 15, at a point between the pivots 12 and 13, to the extension 7 of the handle, the pivot 15 being located also nearer one end of the handle 14 than the other end thereof. 70

It will be observed from an inspection of the drawings that the bolt 10 is considerably longer than the bolt 11 and that the former bolt extends over the handle 6 of the cover and that when the operating handle is in the 75 full line position shown in Fig. 1 of the drawings, it overlies the said bolt 10. At this point it will be readily understood that by swinging the handle lever from full to dotted line position shown in Fig. 1 of 80 the drawings, the bolts 10 and 11 will be drawn toward each other, generally speaking, and at their outer ends will be withdrawn from the openings 8 although they will retain their engagement in the guides 9. 85

When the bolts are thus retracted, the cover may be removed from the container which it closes and upon reinsertion in the mouth or neck of the container and a return of the operating handle to full line position shown 90 in Fig. 1, will be securely locked against such removal, it being of course understood that the mouth or neck of the container is formed with openings or with sockets for the engagement of the outer ends of the 95 bolts 10 and 11, said sockets being indicated in Fig. 2 of the drawings by the numeral 16. It will be observed, further, from an inspection of Fig. 1 of the drawings that inasmuch as the bolt 10 extends 100

above the handle 6 and in fact rests thereon, and the operating handle 14 is arranged to overlie the bolt 10, when the cover is locked to the container, the locking device embodying these several elements will in no 105 way interfere with the grasping of the cover handle and furthermore the elements of the locking device will be protected against injury to a greater or less degree. The operating handle 14 is formed, near its end opposite its pivoted end, with an opening 17 which registers with an opening 18 formed 110

in the bolt 10 when the bolt and handle are in the full line position shown in Fig. 1 of the drawings. Also, the handle 6 is formed with an opening indicated by the 5 numeral 19 and this opening registers with the opening 18. As a consequence when the cover has been locked to the container which it is designed to close, the hasp of a padlock 20 or any other suitable locking or 10 sealing device may be secured through the openings 17, 18 and 19 and the operating handle either held positively against movement to position to retract the bolt or prevented from being so moved without indicating this fact.

What is claimed is:

A container cover comprising a body, a handle upon the body, bolts slidable upon the handle, the bolts at their outer ends be-

ing arranged to cooperate with the neck of a container upon which the cover is fitted, and an operating handle pivoted to the inner ends of the bolts and to the handle at a point between the first mentioned pivots, the handle, when the bolts are extended, being arranged to overlie one of the bolts, the said handle, the said bolt which it overlies, and the handle upon the cover being formed with openings adapted to register when the bolts are extended.

In testimony that I claim the foregoing as my own, I have hereto affixed my signature in the presence of two witnesses.

BENJAMIN VIGDAL.
